ATTORNEY.

UNITED STATES PATENT OFFICE.

THOMAS BENFIELD, OF NEWARK, NEW JERSEY.

DESIGN FOR A WATCH-CASE.

SPECIFICATION forming part of Design No. 21,489, dated April 19, 1892.

Application filed March 17, 1892. Serial No. 425,372. Term of patent 7 years.

To all whom it may concern:

Be it known that I, THOMAS BENFIELD, a subject of Her Majesty the Queen of Great Britain, residing at Newark, in the county of Essex and State of New Jersey, have invented and produced a new and original Design for Watch-Cases, of which the following is a specification, reference being had to the accompanying drawings, forming part thereof.

Figure 1 is a plan view for a watch-case, showing my new design. Fig. 2 is a sectional view taken on the line X X of Fig. 1.

The essential feature of this design consists of a series of ribs A and corrugations B, disposed or arranged, as shown in Fig. 1, upon the opposite sides of a plain band C. The

ribs A, where they meet the plain band C, end in a scroll D, as shown in Fig. 1. The several portions may, it is manifest, be engraved, chased, or otherwise ornamented, as desired.

It is apparent that this design is also applicable to lockets and other similar articles.

Having described my invention, what I claim as new, and desire to secure by Letters Patent, is—

The design for a watch-case, as herein shown and described.

THOMAS BENFIELD.
